DESIGN FOR A TEXTILE FABRIC

Philip A. Vogelman, New York, N. Y., assignor to Onondaga Silk Company, Inc., New York, N. Y.

Application February 14, 1936, Serial No. 61,175

Term of patent 3½ years

To whom it may concern:

Be it known that I, Philip A. Vogelman, a citizen of the United States of America, residing in the Borough of Manhattan, in the county of New York, city and State of New York, have invented a new, original, and ornamental Design for a Textile Fabric, for which the following is a specification, reference being had to the accompanying drawing, forming part thereof.

The figure is a plan view of a textile fabric showing my new design with a complete design unit enclosed by dot and dash lines.

I claim:

The ornamental design for a textile fabric substantially as shown and described.

PHILIP A. VOGELMAN.
